(**) Term: **15 Years**(57) **CLAIM**(21) Appl. No.: **29/692,091**

The ornamental design for a smoke detector chamber, as shown and described.

(22) Filed: **May 22, 2019**

DESCRIPTION

(63) Continuation-in-part of application No. 16/206,268, filed on Nov. 30, 2018, which is a continuation-in-part of application No. 16/181,878, filed on Nov. 6, 2018.

FIG. 1 is an exemplary perspective view of a smoke detector chamber, according to an embodiment;

(51) **LOC (13) Cl.** **10-05**

FIG. 2 is an exemplary top plan view thereof, according to an embodiment;

(52) **U.S. Cl.**

FIG. 3 is an exemplary bottom plan view thereof, according to an embodiment;

USPC **D10/106.5**

FIG. 4 is an exemplary side view of a smoke detector chamber, according to an embodiment;

(58) **Field of Classification Search**

FIG. 5 is an exemplary alternate isometric view of a smoke detector chamber, according to an embodiment;

USPC D10/104.1, 104.2, 106.1–106.95, 108, D10/121, 123–126
CPC G08B 17/00; G08B 17/06; G08B 17/10; G08B 17/11; G08B 17/12; G08B 17/103; G08B 17/107

FIG. 6 is an exemplary alternate side view of a smoke detector chamber, according to an embodiment;

See application file for complete search history.

FIG. 7 is an exemplary alternate perspective view of a smoke detector chamber, according to an embodiment; and,

(56) **References Cited**

FIG. 8 is an exemplary alternate perspective view of a smoke detector chamber, according to an embodiment.

U.S. PATENT DOCUMENTS

In the drawings, the broken lines depict portions of the smoke detector chamber which form no part of the claimed design.
